UNITED STATES PATENT OFFICE.

MAX A. SKALL, OF NEW YORK, N. Y.

DISPLAY-CABINET.

1,205,040.

Specification of Letters Patent. Patented Nov. 14, 1916.

Application filed February 7, 1916. Serial No. 76,569.

To all whom it may concern:

Be it known that I, MAX A. SKALL, a citizen of the United States, and residing at New York city, in the county and State of New York, have invented certain new and useful Improvements in Display-Cabinets, of which the following is a specification.

This invention relates to improvements 10 in display cases for cigars or similar articles, affording facilities for inspection, and protection from undue handling and preservation of the inclosed cigars at the proper humidity. 15 Particular advantages gained by my invention are ease of operation of placing a box of cigars in the display case and a full exposure of cigars, and of the display lid of the cigar box, to the eyes of the observer. 20 With these and other objects in view the invention consists in certain novel details of construction and arrangements of parts hereinafter described and particularly set forth in the appended claims. 25 Reference is to be had to the accompanying drawings, forming part of this specification, in which—

Figure I is a perspective view of the display cabinet. Fig. II is a front elevation 30 of my display cabinet when in closed condition. Fig. III is a side elevation of the left side of the case. Fig. IV is a side elevation of the right side of the case. Fig. V is a front elevation of the display case in 35 fully opened condition. Fig. VI is a sectional side elevation of a filled display case on the line A—A of Fig. V showing the upper door in closed and the lower door in opened position.

Similar letters of reference indicate corresponding parts throughout the various figures.

Referring to the drawings 1 represents the horizontal bottom plate and 2 the vertical rear wall of my display cabinet which are preferably made from fibrous material covered on one side by sheet metal and framed by U-shaped metal channels to protect their edges. The uppermost portion of plate 2 is bent toward the front in horizontal direction to form a narrow ledge 2^a. The sides of the cabinet are formed by plates 4 and 5 made of the same material as the bottom and rear plates and preferably soldered to them. The shape of these side plates conforms to a right angled tri-

angle resting on its shorter leg; from this triangle the lower front corner is cut away, in form of a small triangle similar to the main triangle, to form the short sides 4^b and 5^b in direction perpendicular to the sides 4^a and 5^a. A plate 3 is attached to sides 4 and 5 and bottom 1 along the lines 4^b and 5^b.

The front of the cabinet is formed by two 65 glass plates 6 and 7, each contained in a separate frame formed of U shaped channels and covering the front opening formed by plates 4, 2^a, 5 and 3. The vertical edges of these frames 6^a, 7^a, and 6^b, 7^b rest on 70 edges 4^a and 5^a of side plates 4 and 5. Plate 6 covers the upper half of the front opening and channel 6^a at its frame is connected by means of suitable vertical hinges 8, to edge 5^a of plate 5. The other vertical channel, 75 6^b, of this frame is provided with a suitable catch 9 which engages a pin 10 on side plate 4 to lock plate 6 in its closed position. Channel 6^c forms the lower horizontal edge 80 of plate 6 and to this edge the upper horizontal edge of the corresponding channel 7^c of plate 7 is fastened by means of hinges 11. The vertical channel 7^b of this plate is provided with a suitable handle bar 12 permitting to swing plate 7 upward through 85 an angle of 180 degrees when it finds a rest on the front side of plate 6. (See Fig. VI.) On the inside of the casing I have arranged two angle bars 13 fastened to side plates 4 and 5 and parallel to sides 4^a and 5^a of these 90 plates. These angle bars form a rest for the bottom 14^a of the displayed cigar box 14. The front side 14^b of this box rests on plate 3 which forms an angular bottom of the cabinet and the front edge 15^b of the 95 opened lid 15 of the cigar box finds a support against the back 2 of the cabinet and is protected by the narrow ledge 2^a attached thereto. To keep the air inside of the casing at the proper humidity I have provided 100 a humidor 16 preferably made of perforated metal. This humidor rests on the upper edges 13^a of the angle bars 13 and leans against the back 2 of the casing. It is preferably made in shape of a horizontal prism 105 of triangular or semi-circular cross section, and its interior is filled with a moisture absorbent material 17. The casing rests preferably on rubber buffers 18 attached to plate 1.

The advantages of my display case are 110 principally the ease with which a box of cigars or similar articles may be placed

therein, if the catch 9 is unlocked, both doors may be opened simultaneously by means of handle bar 12 the opened cigar box is placed with its front board 14^b on plate 3 of the cabinet and the rest of the box and lid fall automatically into their proper position in the casing. Both doors are then closed together and catch 9 locked; 10 cigars may now be dispensed, by only lifting the lower door 7. In similar display cases the lid of the cigar box must be held by hand until the case is closed. As the lid of the cigar box rests in the same plane with the top of the box proper, the pur- 15 chaser obtains a full view of both, cigars and display lid simultaneously and not only a shortened projection of either of them when looking at the display case. The small open space formed between the front 20 part of plate 1 and plate 3, can be utilized for storing advertising cards, matches or the like. The extended bottom adds considerably to the stability of the case.

Having thus described my invention, what 25 I claim as new and desire to secure by Letters Patent is:

1. A display cabinet of the kind described, comprising a chamber for the reception of a box and its open lid, the slanted front 30 side of the cabinet forming a plane covering the lid and opening of said box, and consisting of two transparent doors, the lower door being pivotally attached to the upper door and the upper door to one of 35 the side plates of the cabinet.

2. A display cabinet of the kind described comprising a chamber quadrangular in cross-section, means in said chamber to support a box and its open lid in slanted position, the lid resting in the plane of the front opening of said box, a slanted bottom plate to support the front side of the box and a door consisting of two transparent plates, covering the front of the cabinet, one of 45 said plates being adapted to swing around a horizontal axis and both plates around a second axis.

3. In a display cabinet for cigars, a casing whose quadrangular cross-section is formed by a rear side, a slanted front side 50 and two bottom plates, one of said bottom plates being slanted to support the displayed box, the other bottom plate being extended beyond the casing to act as a stabilizer for the same, the front side consisting of two 55 hinged panels forming doors, the hinges of one panel being arranged perpendicularly to the hinges of the other panel.

4. A display cabinet for cigars or the like, consisting of a single chamber of quadrangular cross-section accommodating the displayed box and its lid in slanted position, the front of the lid forming a plane with the front opening of the displayed box; a door of two transparent plates arranged in the same plane and forming the front side of the casing, means to move one of said plates independent of the other and means to move both plates simultaneously.

5. A display cabinet of the kind described 70 forming in transverse section an irregular quadrangle of two short and two long sides; each short side being perpendicular to one of the longer sides, the slanted front side of the cabinet consisting of two transparent 75 doors, one of said doors being adapted to swing on an axis parallel to one of the side plates and the other door on an axis perpendicular to the first one.

6. A display cabinet of the kind described 80 forming in transverse section an irregular quadrangle, consisting of a stationary rear side, a base plate perpendicular thereto, a slanted front side forming the door of the cabinet and a short side forming the support for the front side of a box displayed 85 in the cabinet; said door consisting of two transparent panels and means thereon to swing both of said panels simultaneously around the same axis or a single panel 90 around an axis perpendicular to the first one.

MAX A. SKALL
